CLAIM

We claim the ornamental design for a display stand, as shown and described.

DESCRIPTION

FIG. 1 is a front perspective view of a display stand; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a right, rear elevation view thereof, shown in an alternate position and in an environment of use; FIG. 9 is a top view thereof, shown in an alternate position and in an environment of use; FIG. 10 is a top view thereof, shown in an alternate position and in an environment of use; FIG. 11 is a right side view thereof, shown in an environment of use; and, FIG. 12 is a right side view thereof, shown in an environment of use.

The broken lines shown in FIGS. 2-5 and 7 illustrate portions of the display stand that form no part of the claimed design. The broken lines illustrating the monitor and wires in FIG. 8 and the monitor in FIGS. 9-12 are environment that form no part of the claimed design, while the remaining broken lines in FIGS. 8-12 illustrate portions of the display stand that form no part of the claimed design.
